Primary Examiner — David Muller*Assistant Examiner* — Nathan Johnston(74) *Attorney, Agent, or Firm* — LRK Patent Law Firm(57) **CLAIM**

The ornamental design for valve stopper for syringe, as shown and described.

DESCRIPTION

FIG. 1 is a perspective view of the valve stopper for syringe showing our new design;

FIG. 2 is a front elevational view thereof;

FIG. 3 is a rear elevational view thereof;

FIG. 4 is a left side elevational view thereof;

FIG. 5 is a right, side elevational view thereof;

FIG. 6 is a top plan view thereof;

FIG. 7 is a bottom view thereof;

FIG. 8 is a cross sectional view thereof which is taken along the line 8-8 in FIG. 6;

FIG. 9 is an environmental perspective view thereof; and,

FIG. 10 is an environmental perspective view thereof.

The features shown in broken lines depict environmental subject matter only and form no part of the claimed design.

1 Claim, 10 Drawing Sheets(56)
